UNITED STATES PATENT OFFICE.

CHARLES A. CONKLE, OF PHILADELPHIA, PENNSYLVANIA.

FIRE ESCAPE.

Application filed August 9, 1926. Serial No. 128,038.

This invention relates to fire escapes, particularly to that class thereof which are adopted to be manually extended, to serve windows adjoining a fixed portion of the 5 fire escape.

Inasmuch as the front upper windows of a dwelling are usually bed room windows, it is desirable to have fire escapes opposite such windows for quickest exit from a burning 10 building, and on account of the fire escapes being thus put on the front of a building, it is important that the construction of the fire escape conform to the ornate appearance 15 of the building, rather than mar the same, as is done by some common forms of fire escapes now in use.

It is therefore one of the objects of this invention to provide a form of fire escape which will serve as a balcony, individually, 20 to be in front of one or a small group of windows, and have extensions to be pulled out like drawers of a table, to come opposite adjoining windows or groups of windows on either side of the fixed balcony.

Such a fire escape will enable a person to leave thru the window of a burning building and enter a window of an adjoining building to escape in safety.

A further object is to provide a fire escape 30 which can be attached to a building in a simple and inexpensive manner to materially reduce the cost of attaching the same to the building.

With these and other objects, my invention 35 resides in certain construction, one embodiment of which is illustrated in the drawings, is hereinafter described, its use is explained and what I claim is set forth.

In the drawings, 40 Figure 1 is a front elevation of a fire escape embodying my invention.

Figure 2 is a fragmental top plan of the fire escape shown in Figure 1.

Figure 3 is a vertical section taken on the 45 line 3—3 of Figure 1.

Figure 4 is an enlarged vertical section of a part of the fixed and sliding frames assembled therewith.

Figure 5 is a front elevation of a part of 50 a building front, showing two balcony fire escapes, embodying my invention and arranged to accommodate six windows in a row.

Like figures of reference refer to like parts.

In the figures, there is shown a fixed platform frame 10, formed by channel irons 11

and 12, with slats 13 fixed or riveted thereto, and fixed to wall brackets 14 and 15, which consists of angle irons 16 and 17 fixed to the wall 18, and riveted together. The 60 brackets 14 and 15 extend beyond the channel iron 11, to form an extended support for the braces 19 and 20, respectively, which are riveted thereto. Vertical slats 21 form the front wall of the fire escape and are fixed 65 at the top to a tube 22, which has caps 23 and 24 fixed to its ends. The end slats 25 and 26 are fixed to the respective braces 19 and 20.

Within the fixed frame formed by the 70 channel irons 11 and 12 is a sliding frame 27, formed by the angle irons 28 and 29, to which are fixed the slats 30. The angle irons 28 and 29 rest upon rollers 31, which enter notches in the bottom flange of the channel 75 iron 11 and are mounted pivotally upon the brackets 32, which are riveted to the channel iron 11. The angle irons 28 and 29 ride upon their edges on the rollers 31. The sliding frame 27 is U-shaped, having a cross 80 angle iron 33 fixed to the outer ends of the angle irons 28 and 29.

To the cross angle iron 33, is fixed a pipe rail 34, which has a vertical portion 35 parallel with the wall 18, a horizontal portion 36, 85 perpendicular to the wall 18, and a horizontal portion 37, parallel to the wall 18, in sliding engagement with the cap 23 and entering the tube 22. Upon the inner end of the pipe rail 34, and in sliding engagement 90 with the tube 22, is a flange 38 fixed to the rail 34. Between and fixed to the rail portion 36 and the cross angle iron 33 are slats 39, forming an end wall to the fire escape.

Out of the opposite end of the platform 95 frame 10, projects a sliding frame 40, which is U-shaped, having angle irons 41 and 42, riding with their flanges 43 upon the rollers 31, and having the angle irons 41 and 42 connected by slats 44. The angle irons 41 and 42 are connected at their outer ends with the cross angle irons 45. The angle irons 41 and 42 lie closely within the angle irons 28 and 29, while the angle irons 28 and 29 lie closely within the channel irons 11 and 12, as shown particularly in the enlarged section of Figure 4. All angle irons and channel irons that slide within one another are parallel.

To the cross angle iron 45 is fixed a pipe 110 rail 46, which has a vertical portion 47 parallel with the wall 18, a horizontal portion

48, perpendicular to the wall 18 and a horizontal portion 49 parallel with the wall 18, and in sliding engagement with the cap 24 and entering the tube 22. Upon the inner 5 end of the pipe rail 46, in sliding engagement with the inside of the tube 22, is a flange 50, fixed to the rail 46. Between, and fixed to the rail portion 48 and the cross angle iron 45, are slats 51, forming another end wall to 10 the fire escape.

In Figure 5 are shown six windows 52, 53, 54, 55, 56 and 57. Opposite the windows 53 and 56 are fire escapes 58 and 59, similar in construction to the one above described 15 and illustrated in the other figures. The sliding frames which can be drawn out of ends of the fire escape are shown in extended positions by the broken lines 60 and 61, and 62 and 63. Thus one extension at 60 20 comes opposite window 52, when drawn out by pulling on the rope, cable or chain 64. The extension at 61, comes opposite window 54. The extension at 62 comes opposite the window 54. The extension 62 comes opposite 25 the window 55. The extension 63 comes opposite the window 57, pull lines 65, 66 and 67 being provided for the extensions at 61, 62 and 63. These extensions are supported on the cantilever principle, when they 30 are drawn out. When they are pushed in, they form closed ends to the fire escape which then appears as a balcony.

A building having a row of windows, can be provided with such fire escapes for every 35 third window, and the extensions will accommodate the remaining two-thirds, effecting a considerable saving in construction, as well as on the cost of mounting the fire escape.

Although no means are shown upon which 40 to descend from the fire escape, any suitable means can be provided for the purpose but it would be preferable to use some means which can be folded or rolled up in a small space, rather than a fixed ladder, if it is desired to have the fire escapes show as individual balconies on the face of the building.

While I have shown only one embodiment 45 of my invention in the drawings, other forms can be devised for the purpose, without departing from the spirit and scope of my invention. I therefore do not wish to be confined to the one embodiment thereof herein shown and described.

I claim:

55 1. A fire escape comprising a fixed platform frame, means for supporting said fixed platform frame upon a wall, spaced and parallel channel irons to said frame having their flanges horizontal, with the edges thereof turned in, a second platform frame 60 within said fixed platform frame and in sliding engagement therewith, having longitudinal members fitting within said channel irons, the slide thereon, adapting said second 65 platform frame to be pulled out as an exten-

sion cantilever platform to said fixed platform frame, and means extending beyond the said second frame attached thereto and adapted to be reached by an operator to enable him to pull the said second frame 70 to himself for entering thereon.

2. A fire escape comprising a fixed platform frame, means for supporting said fixed frame, a second platform frame, in sliding keyed engagement with said fixed frame, an 75 upstanding wall to said fixed frame, a longitudinal wall member to said wall, a second upstanding wall fixed to said second platform frame at its outer end, and a hand rail to said second wall, in sliding engagement with said longitudinal wall member, and means extending beyond the said second frame attached thereto and adapted to be reached by an operator to enable him to pull the said second frame to himself for entering 80 thereon.

3. A fire escape adapted for attachment to the wall of a building, comprising a channel iron frame, two spaced channel irons parallel with said wall and forming part of 90 said frame, a flat door to said frame, extending between said channel irons, a support for said frame, attached to said wall, said channel irons having their flanges turned inwardly to form a track, and a flat 95 longitudinal member forming an auxiliary floor to said first mentioned floor, and being in sliding engagement with said track positioned between said channel irons, said member being adapted to be pulled partly 100 out from said channel iron frame, to afford an extension to the floor of said channel iron frame, and other means extending beyond and attached to said member adapted to be reached by an operator to enable him to 105 pull said member to himself for entering thereon.

4. A fire escape adapted for attachment to a wall of a building, comprising a channel iron frame, two spaced channel irons parallel with said wall and forming part of 110 said frame, a flat floor to said frame, extending between said channel irons, a support for said frame, attached to said building, said channel irons having their flanges 115 turned inwardly to form a track, a flat longitudinal member forming an auxiliary floor to said first mentioned floor, and being in sliding engagement with said track, positioned between said channel irons, said member being adapted to be pulled partly out from said channel iron frame, to afford an extension to the floor of said channel iron frame, a guard rail in fixed elevated relation to the outer of said channels, a second 120 rail in sliding telescopic engagement with said guard rail, said second rail being fixed with relation to said sliding member, and other means extending beyond and attached to said member adapted to be reached 125 130

by an operator to enable him to pull said member to himself for entering thereon.

5. A fire escape forming a balcony to a building, and comprising a main platform fixed to a wall of said building, a floor to said platform, an outer front wall fixed to stand up from the outer part of said platform, parallel to said building, a wall at one end of said balcony, perpendicular to said building, between the same and the end of said front wall, an auxiliary platform in sliding engagement with said main platform and adapted to be pulled partly out from said main platform, a floor to said auxiliary platform, an auxiliary wall to said auxiliary platform, having a portion at right angles to the remaining portion in sliding engagement with said front wall, and means attached to and extending beyond said auxiliary platform adapted to be reached by an operator to enable him to pull the said auxiliary platform to himself for entering thereon.

6. A fire escape adapted for attachment to a building, comprising a platform frame fixed to said building, means for supporting said frame on said building in fixed relation

thereto, a second platform frame on said first mentioned platform frame, in sliding engagement therewith, for forming an extension to the platform thereof, means for retaining said frames in parallel relation, and other means attached to and extending beyond said second platform frame, adapted to be reached by an operator to enable him to pull the said second platform frame toward himself, to enable him to enter thereon.

7. A fire escape comprising a fixed platform frame, two other platform frames in sliding engagement with one another and with said fixed frame, each of said two platform frames last mentioned, being adapted to slide out as a cantilever from said fixed platform frame, from an end thereof, and to form an extension of an appreciable and safely usable extent to the platform of said fixed platform frame, and means attached to each of said last mentioned platform frames, extending beyond the same to be reached by an operator to enable him to pull the slideable frame toward himself, and to enable him to enter thereon.

CHARLES A. CONKLE.
